(57) **CLAIM**

The ornamental design for a push pull knob, as shown and described.

DESCRIPTION

FIG. 1 is a perspective view of my new push pull knob;
FIG. 2 is a front view thereof;
FIG. 3 is a top view thereof;
FIG. 4 is a right side view thereof;
FIG. 5 is a back view thereof;
FIG. 6 is a left side view thereof;
FIG. 7 is a perspective view of the push pull knob of FIG. 1 shown in a first example environment; and,
FIG. 8 is a perspective view of the push pull knob of FIG. 1 shown in a second example environment.

The portion of the push pull knob depicted in broken lines in FIGS. 1–6 and the environmental structures depicted in broken lines in FIGS. 7 and 8 are shown by way of example and form no part of the claimed design.
